The ornamental design for an identity identification device, as shown and described.

Dec. 14, 2017 (CN) 2017 3 0639395

DESCRIPTION(51) **LOC (12) Cl.** **14-02**

FIG. 1 is a front view of an identity identification device showing the new design.

(52) **U.S. Cl.**

FIG. 2 is a rear view thereof;

USPC **D14/383; D14/374**

FIG. 3 is a left side view thereof;

(58) Field of Classification Search

FIG. 4 is a right side view thereof;

USPC D10/46; D14/371, 374, 383

FIG. 5 is a top view thereof;

CPC G09F 15/0025; G09F 15/0062; G09F

FIG. 6 is a bottom view thereof;

15/0068; G06F 1/16; G06F 1/1613; G06F

FIG. 7 is a front, top and left perspective view thereof;

1/133308; G06F 1/1601; G06F 3/037;

FIG. 8 is a rear, bottom and right perspective view thereof;

G06F 1/162; F16M 11/02; F16M 11/10;

FIG. 9 is a cross-sectional view thereof taken along line 9-9 in FIG. 1; and,

F16M 11/00; F16M 11/06; F16M 11/18;

FIG. 10 is a cross-sectional view thereof taken along line 10-10 in FIG. 1.

F16M 11/045; F16M 11/105; F16M

11/041; F16M 11/126; F16M 11/04;

F16M 11/24; F16M 13/02; A47F 5/00;
